(57) **CLAIM**

The ornamental design for a connector for drinks inflation device as shown and described.

DESCRIPTION

FIG. 1 is a first perspective view of a connector for drinks inflation device showing our new design;

FIG. 2 is a second perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is a perspective view thereof shown in a condition of use; and,

FIG. 10 is a perspective view thereof shown in another condition of use.

The broken lines in the drawings illustrate portions of the connector for drinks inflation device which form no part of the claimed design.

The broken lines of the high pressure gas release device and the drinks inflation device applied to the connector for drinks inflation device in FIGS. 9 and 10 are used to indicate environmental structures and form no part of the claimed design.
